UNDERGARMENT

Philip H. Robbins, New York, N. Y., assignor to
 Poirette Corsets, Inc., New York, N. Y., a corporation of New York

Application February 17, 1934, Serial No. 711,705

11 Claims. (Cl. 2—30)

This invention relates to an undergarment, and has for its object to provide, in a manner as hereinafter set forth, a garment of the class referred to, which will not only adjust itself to different movements of, but at the same time snugly fit around the bust, the sides and the back of the body of the wearer and act to prevent the flesh from bulging or creeping out from over the top edge thereof at its sides.

10 A further object of the invention is to provide, in a manner as hereinafter set forth, a garment of the class referred to, to obtain when worn, for the snug fitting around the bust, sides and back of the wearer, and at the same time preventing 15 the top edge thereof from becoming loose and ill-fitting, especially when the wearer sits down.

A further object of the invention is to provide, in a manner as hereinafter set forth, a garment of the class referred to, with means to form a very 20 firm hold of the underarm bust section without the aid of shoulder straps for controlling the bust and diaphragm of the wearer.

A further object of the invention is to provide, in a manner as hereinafter set forth, a garment 25 of the class referred to with elastic and non-elastic means coacting to form a control, which when worn on the body will absolutely lay flat and hug the body in a very effective manner.

A further object of the invention is to provide, 30 in a manner as hereinafter set forth, a garment of the class referred to having means at the front thereof for effecting a purchase over the breast plates which assists in holding the garment firmly in place.

35 A further object of the invention is to provide, in a manner as hereinafter set forth, a garment of the class referred to having means for firmly holding it in position without the employment of back straps.

40 A further object of the invention is to provide, in a manner as hereinafter set forth, a garment of the class referred to having means for holding the bust of the wearer firmly in position and with the elimination of the appearance of the back 45 stretches of the shoulder straps by utilizing such stretches to provide what may be termed a collar band.

The present trend in style in undergarments, such as corsets, brassières and girdles is to have a 50 low back, but undergarments of such type heretofore were open to the objection that they did not fit firmly and their top edges would become loose and ill-fitting, especially when the wearer would sit down. It is the aim of this invention to over- 55 come the objection as aforesaid by providing a

low back, neat fitting undergarment around the bust and under the arms of the wearer with a V-shaped yoke at its front and oppositely extending diagonally disposed elastic elements coacting with the yoke whereby the garment will 60 be held firmly in position; adjust itself to different movements of the body of the wearer; while at the same time be snug-fitting around the bust; taut at its top edge; and snugly fitting the sides and back of the wearer.

65 Further objects of the invention are to provide, in a manner as hereinafter set forth, an undergarment for the purpose referred to, which is simple in its construction, strong, durable, pleasing in appearance, thoroughly efficient for the 70 purpose intended thereby, and comparatively inexpensive to manufacture.

To the above ends essentially and to others which may hereinafter appear, the invention consists of such parts, and such combination of parts, 75 which fall within the scope of the invention as claimed.

In the drawings:

Figures 1, 2 and 3 are respectively front, rear and side elevations of an undergarment, such as 80 a corset, constructed in accordance with this invention and positioned upon the body of a wearer,

Figure 4 is a fragmentary view of the corset in front elevation and upon an enlarged scale,

Figure 5 is a section on line 5—5 Figure 4,

85 Figures 6, 7 and 8 are respectively front, rear and side elevations of an undergarment, such as a brassière, constructed in accordance with this invention and positioned upon the body of a wearer,

Figure 9 is a fragmentary view of the brassière in front elevation and upon an enlarged scale, and

Figure 10 is a fragmentary view in front elevation of the garment provided with a neck or collar band.

90 With reference to Figures 1 to 5, the garment shown thereby is in the form of a corset generally indicated at 12, and which includes a front 13 consisting of a non-elastic panel formed centrally of its lower end with a tapered cutout 14 closed by a resilient gusset 15. The top edge of front 13 consists of a pair of end edge portions 16, 17, a central edge portion 18 and a pair of intermediate edge portions 19, 20, between which is arranged the edge portion 18. The edge portions 16, 17 are arranged above the edge portion 18 and are oppositely inclined with respect to each other. The inclinations of said edge portions 16, 17 are downward from their inner ends. The edge portion 18 is of V-shape contour to provide a pair of 100

95

105

110

oppositely extending stretches. The edge portions 19, 20 are of circular contour and the outer side of each is of greater length than the inner side. The outer side of edge portion 19 merges at 5 its upper end into the inner end of edge portion 16. The inner side of edge portion 19 merges at its upper end into the outer end of one of the stretches of the central edge portion 18. The outer side of edge portion 20 merges at its upper 10 end into the inner end of edge portion 17. The inner side of edge portion 20 merges at its upper end into the outer end of the other stretch of the central edge portion 18. The manner of setting up the top edge of front 13 provides the upper portion of the latter with a central tapered part 21 and a pair of side tapered parts 22, 23 which extend above the part 21.

The garment 12 also includes a pair of sides 24, 25 formed of elastic stretches 26, 27 respectively, and oppositely disposed non-elastic stretches 28, 29 respectively. The stretches 26, 27 are of greater length than the stretches 28, 29 respectively. Each non-elastic stretch is secured to the top of and extends upwardly from an elastic 25 stretch. Each non-elastic stretch has its top edge 30 inclining downwardly from its inner towards its outer side. The top edges 30 of the stretches 28, 29 form flush continuations of the top end edge portions 16, 17 respectively of the front 13.

The garment 12 also includes a non-elastic back 31 formed of two sections 32, 33 having the lower portions of the inner sides thereof secured together as at 34. The non-connected portions of the inner sides of the sections 32, 33 provide a slit 35 which may be closed by coacting fastener devices 36 carried by said sections. The top edge 37 of back 31 is of segmental curvature.

The providing of the sides 24, 25 with the 40 stretches 28, 29 respectively form each side with a high part and a lower part. The high parts of the sides 24, 25 are secured to the sides of the front 13. The low parts of the sides 24, 25 are secured to the sides of the back 31. The latter, as at 38, 39 extends beyond the upper ends of the 45 lower parts of the sides 24, 25 to provide spaced vertical edge portions.

Secured to the edge portions 19, 20 of the top of front 13 are pieces of fabric 40, 41 respectively. 50 The fabric pieces preferably are lace and shaped to extend forwardly from front 13 to provide breast receiving pockets 42. The top edges 43 of the fabric pieces are of convex curvature and form flush continuations of the stretches of edge portion 18 and edge portions 16, 17 of the top edge of the front 13. The fabric pieces are spaced from each other by the tapered part 21 and spaced from the sides 24, 25 by the tapered parts 22, 23 of the front.

60 Anchored to the major part of the length of edge portions 16, 17, to the stretches of the edge portion 18 and to the edges 43 of the fabric pieces 40, 41 is an upstanding yoke 44 of substantially V-shape formed of a pair of oppositely inclined legs 45, 46. 65 The bottom edge 47 of each of the legs conforms in contour to that of a stretch of edge portion 18, an edge portion 18 or 19 and the top edge 43 of a fabric piece. The outer end edge 48 of each leg is positioned adjacent the outer end of an end edge portion 18 or 19, is upstanding and disposed at a slight 70 inclination to the end edge portion and opposes in spaced relation the edge 49 of an extended part 38 or 39 of the back 31. The length of edge 48 of a leg corresponds substantially to the length of the edge 49. The top edge of a leg 45 or 46 consists

of a pair of oppositely inclined stretches 50, 51. The former is of greater inclination and length than the latter. The stretch 50 is arranged inwardly with respect to stretch 51 and has its outer end merge into the inner end of stretch 51. The latter at its outer end merges into the outer end of edge 48. The inner ends of the stretches 50 of the legs 45, 46 merge into each other. The inner ends of bottom edges 47 of the legs 45, 46 merge into each other and their point of emergence aligns with the points of emergence of the stretches 50. The outer ends of the bottom edges 47 of the legs 45, 46 merge into the inner end of the outer end edges 48 of the said legs. The yoke 44 consists of a length of suitable fabric, preferably lace. 80

Arranged between each end edge 48 of the yoke 44 and the edge 49 of an extended part 38, 39 is a substantially oblong diagonally disposed elastic strap 52 of a width slightly less than the length of edges 48 and 49, but of a length to extend to such edges. Each strap stands on its lower lengthwise edge. The straps 52 are oppositely disposed with respect to each other. Each strap is secured to a leg of the yoke as at 53 and to the back 31 as at 54. Each strap is also secured to an 100 end edge portion 16 or 17, as at 55 and to the inclined edge 30 of a non-elastic stretch 28 or 29 of a side 24 or 25, as at 56. When the straps 52 are secured in position, the tension thereof is to be slightly more than that of the material to 105 which they are anchored and which will act to maintain the garment in a position to keep the flesh from bulging out of the garment, especially when the wearer is sitting. The top edge of the straps 52 form a flush continuation of the edge 37 of back 32. The garment 12 is shown as provided with front and back straps 57, but the back straps may be dispensed with and will be hereinafter referred to. 110

With reference to Figures 6 to 9 there is shown 115 in accordance with this invention an undergarment in the form of a brassière. The latter is generally indicated at 58 and includes a front part 59, a pair of side parts 60, 61 and a back part 62 of materially less height than that of the front 120 part 59. The front, sides and back parts of the brassière are formed from connected together lengths or pieces of any suitable fabric, and as illustrated by way of example, such as net or lace. The front part 59 and side parts 60, 61 are constructed in a manner to form a pair of breast receiving pockets 63. The back part 62 consists of two sections 64, 65 capable of being detachably connected as at 66.

The front part 59 has its top edge 67 formed of 130 a pair of oppositely inclined stretches 68, 69. Each stretch extends upwardly at an inclination and upon a slight convex curve from its inner end. The inner ends of the stretches merge into each other at the vertical median of the front 135 part 59.

The side parts 60, 61 form continuations of the front part 59 at the lower portions of the sides of the front. The edge 70 at each side of the front part 59 above a side part 60 or 61 extends 140 at an inward inclination from its lower end and merges into the outer end of a stretch 68 or 69. The top edge 71 of each side part 60 or 61 extends upwardly at an inward inclination and merges into the lower end of an edge 70. The 145 sides of the back part 62 extend above the side parts 60, 61, as at 73 to provide vertically disposed edge portions 74. The top edge 75 of back part 62 is of segmental curvature.

Secured to the stretches 68, 69 of the top edge 150

- 67 of the front part 59, is an upstanding yoke 76 of substantially V-shape formed of a pair of oppositely inclined legs 77, 78, each having an outer end edge 79 substantially corresponding in length 5 to and opposing in spaced relation an edge portion 74. The legs have oppositely inclined bottom edges 80 secured to the stretches 68, 69 as at 81, and which at their outer ends merge into the inner ends of the edges 79. The legs have oppositely inclined upper edges 82, and which at their outer ends merge into the outer ends of the edges 79. The yoke 76 is formed of a length of fabric preferably similar to the material of which the brassière is made.
15. Arranged between each end edge 79 of the yoke 76 and an edge portion 74, is a diagonally disposed elastic strap 83 of a width slightly less than the length of edge 79 or edge portion 74, but of a length to extend to the edge 79 and edge portion 74. The straps 83 are oppositely disposed with respect to each other. Each strap 83 is secured to a leg of the yoke as at 84, to an edge portion 74 as at 85 and to an inclined edge 70 and an inclined edge 71 as at 86. The straps 83 when connected in position are tensioned similar to the straps 52.
- Front and back straps 87 as shown are connected to the brassière.
- With reference to Figure 10, a garment in accordance with this invention is designated 88 and has connected thereto what may be termed a collar band 89 for the purpose of eliminating the appearance of back straps.
- The yoke and diagonally disposed elastic straps 35 coact to provide a control means which when the garment is worn, will cause the latter to fit neatly around the bust and beneath the arms of the wearer, and further whereby the garment will adjust itself to different movements of the body, 40 while at the same time the yoke will fit snugly around the bust and the sides and back are held snugly to the body of the wearer. The yoke and strap further coact to provide for the garment fitting the body of the wearer in a manner to prevent the creeping or bulging of the flesh over the top edges of the sides of the garment; to prevent the top edge of the garment becoming loose or ill-fitting; gives the wearer a purchase over the breast plates assisting in holding the garment 45 firmly in place; for controlling the bust and diaphragm of the wearer; and snugly fit the wearer especially when one sits down.
- What I claim is:—
1. An undergarment including front, back and side parts, said back having side edge portions extending above the rear side edges of said side parts, said side parts having oppositely inclined top edges, a yoke secured to, across and extended above the top of said front part, and oppositely extending diagonally disposed resilient straps secured at one end to the ends of the yoke, at their lower edges to the top edges of the side parts and their other end to said edge portions 55 of said back part.
2. An undergarment including front, back and side parts, said back having side edge portions extended beyond a side edge of each of said parts, a substantially V-shaped yoke extending from 60 and across the top of and being secured to said front, said yoke being formed with a pair of end edges disposed in parallel spaced relation, and a pair of oppositely extending diagonally disposed elastic elements, said elements being secured at one end to said end edges and at the other end 65 to said edge portions and being anchored to said front and side parts.
3. An undergarment including front, back and side parts, said back having side edge portions extended beyond a side edge of each of said parts, a substantially V-shaped yoke extending from 70 and across the top of and being secured to said front, said yoke being formed with a pair of end edges disposed in parallel spaced relation, a pair of oppositely extending diagonally disposed elastic elements, said elements being secured at one end to said end edges and at the other end to said edge portions and being anchored to said front and side parts, said side and front parts having downwardly inclined top edges, an inclined edge of the front part forming a flush continuation of an inclined edge of a side part, and the points of anchorage between said elements and said front and side parts being on the inclined edges of such parts.
4. An undergarment comprising a body portion including a front part, a yoke secured to the top of said front part, said body portion including 80 side parts and a back part connected with the side parts, the said back part extending above the side parts at the point of connection of the side parts with said back part, and elastic elements of strap-like form having the ends thereof connected to said yoke and to said extended portion of the back part at spaced points 85 of the latter and being secured at the lower edges thereof to said front and side parts.
5. An undergarment comprising a body portion including a front part, a yoke secured to the top of said front part, said body portion including 90 side parts and a back part connected with the side parts, the said back part extending above the side parts at the point of connection of the side parts with said back part, and elastic elements of strap-like form having the ends thereof connected to said yoke and to said extended portion of the back part at spaced points 95 of the latter and being secured at the lower edges thereof to said front and side parts.
6. An undergarment comprising a body portion provided at the top of its front with a continuous yoke extended upwardly therefrom and at the upper end of its back with a pair of spaced vertical edge portions disposed lengthwise with respect thereto, said yoke having a pair of upstanding end edges arranged above and spaced 100 from said vertical edge portions, and a pair of oppositely extending diagonally disposed elastic elements interposed between said end edges and vertical edge portions, said strap being secured at one end to the said end edges and at their other end to said vertical edge portions, and said elements including lower portions secured to said body portion between said end edges and said vertical edge portions.
7. An undergarment comprising a body formed 105 of a front part, a pair of side parts and a back part joined together, said body being formed with oppositely extending downwardly inclined edge portions at the top of the front and side parts, said body having its back part formed with 110 spaced vertical edge portions at and extending upwardly from the lower ends of said inclined edge portions, a yoke extending across and secured to the top of said front part and being formed with a pair of spaced upstanding end edge 115 120 125 130 135 140 145 150

- portions, and oppositely extending diagonally disposed elastic members formed with end edges and an inner lengthwise edge, the end edges of said elements being secured with the upstanding end edge portions of said yoke and with the said vertical edge portions of said back, and the inner lengthwise edges of said elements being secured with said inclined edges.
8. An undergarment comprising a body formed of a front part, a pair of side parts and a back part joined together, said body being formed with oppositely extending downwardly inclined edge portions at the top of the front and side parts, said body having its back part formed with spaced vertical edge portions at and extending upwardly from the lower ends of said inclined edge portions, a yoke extending across and secured to the top of said front part and being formed with a pair of spaced upstanding end edge portions, oppositely extending diagonally disposed elastic members formed with end edges and an inner lengthwise edge, the end edges of said elements being secured with the upstanding end edge portions of said yoke and with the said vertical edge portions of said back, the inner lengthwise edges of said elements being secured with said inclined edges, said yoke including top and bottom edges, the bottom edge of the yoke being secured with the top edge of said front part, said back part including a top edge, and said elements including outer lengthwise edges having their ends flush with the top edge of said yoke and the top edge of said back.
9. An undergarment including a body portion having a front, a pair of sides and a back having spaced edge portions at its upper end, the upper part of said front consisting of an upstanding yoke substantially of V-form having upstanding end edges, and the upper part of said sides consisting of oppositely extending diagonally disposed elastic portions interposed between said end edges and said edge portions, said elastic portions being anchored at one end to said end edges and at the other end to the said edge portions.
10. An undergarment including a body portion having a front, a pair of sides and a back, the upper portion of said front being in the form of a yoke having end edges, said back having its upper portion formed with spaced edge portions arranged below said end edges, the upper end of each of said sides being in the form of an elastic strap, inclining upwardly from rear to front and interposed between one of said edge portions and one of said end edges, and each strap having one end secured to one of said edge portions and its other end secured to one of said end edges.
11. In an undergarment a front part, a pair of side parts, a back part, an upstanding yoke extending transverse of the upper end of said front part and being formed with spaced upstanding edges, means for securing the yoke to said front part, said side parts being formed with oppositely extending inclined top edges, the inclination of said top edges being upwardly from the rear to front, said top edges arranged below the edges of said yoke, said back part having its sides formed at the top thereof with upstanding side edge portions extending above the rear of said side parts, a pair of oppositely disposed diagonally extending substantially oblong resilient straps, each strap being arranged between one of said upstanding edges of the yoke and one of said upstanding edges of said back part, said strap standing on the lower lengthwise edges thereof, means securing one of the ends of a strap to one of said upstanding edges of the yoke, means for securing the other end of a strap to one of the upstanding edges of said back, and means for securing the lower lengthwise edges of the straps to the inclined top edges of said side parts.
